DISPLAY STAND

Michael Sprechmann, Bronx, N. Y.

Application April 8, 1948, Serial No. 19,701

6 Claims. (Cl. 248—199)

1

This invention relates to display structures and more particularly to display devices for use in store show windows, in showcases, on cupboards and other locations for exhibition etc.

It is one of the objects of this invention to provide a very simple, sturdy but sufficiently flexible display device of the aforesaid type which is of practical construction and reliable and efficient in use and operation.

It is another object of this invention to provide means facilitating the display of a set of articles of varying sizes in neat and orderly fashion.

A still further object of the invention is to provide means ensuring the extensibility of the display device so that it may be readily adjusted to carry for display articles of different shapes, dimensions and volume.

It is another object of this invention to provide means affording a relatively small base on which the articles may be mounted for display and on which they are held in a predetermined position whereby the location of the point of gravity of the display device is determined in a most favorable manner.

Still another object of the invention is to provide means rendering the possibility of easily folding or transforming the display device into disassembled condition for storing and shipping purposes.

These and other objects of the invention will be pointed out in the following description and claims and illustrated in the accompanying drawings which disclose, by way of example, the principle of the invention and preferred modes which have been contemplated for applying said principle.

In the drawings:

Fig. 1 is a perspective view of a display device embodying one form of the invention;

Fig. 2 is a perspective view of the base with adjustable back rest forming a part of the display device of Fig. 1;

Fig. 3 is a side elevational view of the display device of Fig. 1 with various articles in position on said device;

Fig. 4 is a side elevational view of the part of the display device of Fig. 2 with some of the articles seen in Fig. 3 placed on said part.

Fig. 5 is a fragmentary elevational view of a forward portion of the display device in modified form.

Referring now more particularly to the drawings there is shown in Fig. 1 a display device 10 embodying the invention, the device being substantially made of wire material and consisting

2

of a base 11 with back rest 12 and further of an upper extension 13 carrying a swingable platform 13a.

As can be seen from Fig. 3 the display device 5 10 may be employed, for instance, to carry a complete set of articles, such as a large dish or plate A which is placed to abut against the extension 14, 15 of the extension 13 and is braced against stops in form of loops 16, 17 forming the forward ends of the back rest 12. Another plate B is placed forwardly of plate A and is retained in its position by means of holding arms 18, 19 carrying the swingable platform 13a, whereby these holding arms 18, 19 with their lower, forwardly projecting bends 18a, 19a press plate B to maintain its position against plate A.

As can be further seen from Fig. 3 a plate C is placed forwardly of plate B and is held in forward ends or stops forming loops 20, 21. These loops 20, 21 constitute also the feet of the base 11 having the substantially parallel arms 22, 23. The upper end of plate C is engaged by transverse portions 18b, 19b forming the transverse or inwardly turned extension parts of holding arms 18, 19 of platform 13a. This plate C thus comes to lie rearwardly of these transverse arm parts 18b, 19b and effectuates a brace or support for platform 13a consisting of an open loop 25, having spaced forwardly directed extension parts 24a, 24b. The open loop 25 is adapted to receive a saucer D and cup E held by said saucer, as seen in Fig. 3.

Within the upper space formed between plate B and plate C and in engagement with the forwardly directed arm portions 18c and 19c is a small dish or plate F which abuts against knee-shaped upper hinges 18d and 19d forming integral parts of holding arms 18 and 19, respectively.

If it is desired to display a set of plates A, B, and C of different dimensions without articles D, E and F, all that is to be done is to withdraw upper extension 13 from sleeve members 26, 27, which are slidably attached to upright arms 28, 29 of U-shaped back rest 12, whereby plates A, B, and C are retained in the position of Fig. 3 with the only exception that plate A comes to lie against the upper end 30 of U-shaped rest 12 forming a slide or carriage on base 11 proper.

As seen in Figs. 2 and 4 base 11 is made of a substantially U-shaped piece of wire material having the rearwardly and downwardly extending transverse member 31 on which base 11 rests and the aforesaid feet forming loops 20, 21. Back rest 12 forms a support or prop made of U-shaped wire and has the rearward loop portions 32, 33

and the forward loop portions or stops 16, 17, which are respectively interconnected with the aforesaid loop portions 32, 33 by connector pieces 34, 35 which extend substantially parallel to and above horizontal arms 22, 23.

It will be realized that back rest 12 may be displaced along arms 22, 23 of base 11 due to the displaceable engagement of loop portions 32, 33 and 16, 17 with horizontal arms 22, 23 as indicated in dot-dash lines in Fig. 2.

Loops 16, 17 have upwardly projecting ends 16a, 17a which form handles for moving back rest 12 relatively to base 11.

Upright arms 28, 29 slidably receive coupling means in the form of sleeve members 26, 27 the inner openings of which are preferably so shaped that each sleeve may enclose two wire pieces, say 28, 29 and 14, 15 whereby said sleeve members may be maintained under friction in any desired position lengthwise of upright arms 28, 29.

Extension 13 is also of U-shaped formation and made of wire material, arms or leg extensions 14, 15 being interconnected by a traverse or cross-piece 36, which, in turn, supports loops 38, 39 which form the ends of the arms 18, 19 of platform 13a.

Platform 13a may thus be swung by means of loops 38, 39 about crosspiece 36 to a position indicated by dot-dash lines as at 37 and rearwardly of U-shaped extension 13 (Fig. 3).

Feet 21 of base 11 are preferably so shaped or bent with respect to horizontal arms 22, 23, respectively, as to provide suitable grooves 40, 41 with which the lowermost end of plate C may engage (Fig. 4).

Fig. 5 shows foot 21 in a somewhat modified form in so far that the same is covered by a rubber or rubberized layer 42 extending either entirely or only along a part of the wire structure 10.

It will be readily gathered from the aforesaid disclosure that the adjustability of the back rest 12 with respect to the base 11 and of the extension 13 with respect to the back rest 12 permits of easy arrangement of the movable parts of this device with respect to each other so that the point of gravity of the display device when loaded with a complete dinner set of crockery or chinaware will be located under most favorable conditions. Such complete set of table ware may consist of a large dinner plate A, salad plate B, soup plate C, saucer D, cup E and dessert plate F which, in accordance with this invention, can be so grouped and displayed on the device that the same remains firm and stable, although a relatively small base is employed.

It is well understood that instead of sleeve members 26, 27 and instead of guide loops 32, 33 and 16, 17 other coupling means can be employed to bring about adjustability of the extension 13 with respect to the back rest 12 and of the back rest 12 with respect to the base 11.

It can thus be seen that there has been provided in accordance with this invention a display stand for a complete set of table crockery or chinaware comprising a substantially U-shaped base including two substantially horizontal arms, a substantially U-shaped back rest, means connected to said back rest and slidably engaging said arms of said base, said back rest including two substantially parallel upright arms, a U-shaped extension, a platform, said U-shaped extension having two substantially parallel upright arm extensions, and coupling means connecting said upright arms and said upright arm exten-

sions, respectively, and for removal from each other, said platform being pivoted to said extension, whereby said platform may assume a position forwardly and rearwardly of said extension, respectively, and above said base.

Although the invention has been described with reference to certain specific embodiments thereof, it is to be distinctly understood that various modifications and adaptations of the arrangements herein disclosed may be made and may readily occur to persons skilled in the art without constituting a departure from the spirit and scope of the invention as defined in the objects and in the appended claims.

Having thus described the invention, what is claimed as new and desired to be secured by Letters Patent, is:

1. A display stand for a complete set of table crockery, chinaware or the like comprising a substantially U-shaped base including two substantially horizontal arms, a substantially U-shaped back rest slidably connected to said base, said back rest including two substantially parallel upright arms, a U-shaped extension, a platform, said U-shaped extension having two substantially parallel upright arm extensions, and coupling means substantially alignedly connecting said upright arms and said upright arm extensions, respectively, and for removal from each other, said platform being pivoted to said extension whereby said platform may assume a position forwardly and rearwardly of said extension, respectively, and above said base.

2. A display stand for a complete set of table crockery or chinaware comprising a substantially U-shaped base including two substantially horizontal arms, a substantially U-shaped back rest, means connected to said back rest and slidably engaging said arms of said base, said back rest including two substantially parallel upright arms, a U-shaped extension, a platform, said U-shaped extension having two substantially parallel upright arm extensions, and sleeve means removably connecting said upright arms and said upright arm extensions, said platform being pivoted to said extension whereby said platform may assume a position forwardly and rearwardly of said extension, respectively, and above said base.

3. A display stand for chinaware and like articles comprising a substantially U-shaped base having two substantially parallel horizontal arms and a transverse member interconnecting said arms, said arms terminating in looped ends, a back rest carried by said base and including an upwardly extending U-shaped support including two substantially parallel leg elements, one of the ends of each leg element being provided with spaced loop portions, a connector piece joining the loop portions of each leg element together, said connector pieces extending substantially parallel to said horizontal arms of said base whereby said back rest is slidably supported by said loop portions on said horizontal arms of said base, extension means for said back rest, and means located on said back rest for removably receiving said extension means, whereby the latter may be moved lengthwise of said U-shaped support and substantially perpendicular to said arms of said base.

4. A display stand for chinaware and like articles comprising a substantially U-shaped base having two substantially parallel horizontal arms and a transverse member at one end of said arms for interconnecting said horizontal arms, the other end of each arm forming a looped end,

a back rest carried by said base and including an upwardly extending U-shaped support including two substantially parallel leg elements having forward ends, the forward end of each leg element being provided with a pair of spaced guide loop portions, a connector piece for each pair of guide loop portions and extending substantially parallel to said arms of said base whereby said back rest is slidably supported through said guide loop portions by and along said arms of said base, and coupling means on said support adapted to slidably and removably receive an extension and for removal from said support.

5. A display stand according to claim 4, wherein one of said guide loop portions of each leg element forms a handle-shaped stop.

6. A display stand for chinaware and like articles comprising in combination a substantially U-shaped base having two substantially parallel horizontal arms and a transverse member interconnecting said arms, said arms terminating in looped ends, said looped ends and said transverse member being shaped and arranged with respect to said arms to form a prop for the latter whereby said arms are spaced from a surface on which said base is placed therefor, a back rest on said

base and provided with an upwardly extending U-shaped support including two substantially parallel leg elements, each leg element being provided with spaced loop portions through which said arms are threaded, a connector piece for each leg element and joining the loop portions of each leg element together, whereby said back rest is slidably supported by said loop portions along said arms of said base, extension means for said back rest, and means on said support for receiving said extension means and for removal therefrom, whereby the extension means may be moved lengthwise of said support and substantially perpendicular to said arms of said base.

MICHAEL SPRECHMANN.
